(57) **CLAIM**

The ornamental design for a front wheel drive shift fork, as shown and described.

DESCRIPTION

FIG. 1 is a front perspective view of our front wheel drive shift fork;

FIG. 2 is a rear perspective view of the front wheel drive shift fork in FIG. 1;

FIG. 3 is a front elevation of the front wheel drive shift fork in FIG. 1;

FIG. 4 is a rear elevation of the front wheel drive shift fork in FIG. 1;

FIG. 5 is a right side elevation of the front wheel drive shift fork in FIG. 1, with the left side being the mirror image thereof;

FIG. 6 is a top plan view of the front wheel drive shift fork in FIG. 1; and,

FIG. 7 is a bottom plan view of the front wheel drive shift fork in FIG. 1.

1 Claim, 7 Drawing Sheets
